Walter L. Elsfelder, New York, N.Y., assignor to
Emerson Plastics Corporation, Bronx, N.Y.

Filed Apr. 22, 1970, Ser. No. 22,572

Term of patent 3½ years

Int. Cl. D15—99

U.S. Cl. D55—1

FIG. 1.

FIG. 2.

FIG. 3.

FIG. 4.

FIG. 5.

FIG. 1 is a front perspective view of a carrier for silicon wafers which are used in the manufacture of semi-conductor devices, showing my new design;

FIG. 2 is a top plan view thereof;

FIG. 3 is a left side view thereof;

FIG. 4 is a bottom plan view thereof; and

FIG. 5 is a front elevational view thereof.

The design is symmetrical whereby the right side view is identical to the left side view and the rear elevational view is identical to the front elevational view.

I claim:

The ornamental design for a carrier for silicon wafers which are used in the manufacture of semi-conductor devices, substantially as shown and described.
